FIG. 7 Inventor
W.E.Law

By *Kimmel & Crowell*
Attorneys

UNITED STATES PATENT OFFICE

2,519,671

SHAKER

William E. Law, Windsor, Calif.

Application April 21, 1947, Serial No. 742,885

2 Claims. (Cl. 222—142.9)

1

This invention relates to an improved condiment holder, and more particularly to a dispenser for dispensing selectively salt and pepper, or other table condiments, from one receptacle.

It is an object of this invention to provide a dispenser of the kind to be more specifically described hereinafter, having a body divided into a plurality of chambers in which certain condiments may be contained, the chambers being of various sizes in relation to the relative amount of condiments usually used.

Another object of this invention is to provide a dispenser of this type, having a cap or cover which may be fixed to the upper open end of the dispenser by slightly rotating the cover and having a selector plate rotatably carried by the cover for selectively positioning openings in the plate with the chambers in the body.

Another object of this invention is to provide a novel means of securing such a selector plate to a removable cover on a dispenser of this kind, which means consists primarily of correlated grooves on the cover and on the plate, and a spring disposed in the groove between the two members.

A still further object of this invention is to provide a dispenser of this kind in which the cover may readily be removed for filling the body of the dispenser, and the selector plate being carried by the cover will be removed at the same time without disturbing the relation of the plate to the cover.

With the above and other objects in view, my invention consists in the arrangement, combination and details of construction disclosed in the drawings and specification, and then more particularly pointed out in the appended claims.

In the drawings,

Figure 1 is a top plan view of a dispenser constructed according to an embodiment of this invention,

Figure 2 is a vertical section taken on the line 2—2 of Figure 1,

Figure 3 is a horizontal section taken on the line 3—3 of Figure 2,

Figure 4 is a horizontal section taken on the line 4—4 of Figure 2,

Figure 5 is a horizontal section taken on the line 5—5 of Figure 2,

Figure 6 is a fragmentary vertical section taken on the line 6—6 of Figure 5,

Figure 7 is a top plan view of the spring removed from the dispenser.

Referring to the drawing, the numeral 10 designates generally a frustro-conical body made of

2

metal, plastic, or other suitable material, for enclosing salt and pepper, or other table condiments.

The body 10 is formed with annular outer walls 11 and a transverse wall 12 fixed to or formed on the body 10, for dividing the interior of the body into a pair of chambers 14 and 15. The upper end of the transverse wall 12 is disposed substantially centrally of the upper open end of the body 10, and the lower end of the transverse wall 12 is fixed to or formed on the outer walls 11, spaced upwardly from the bottom or apex of the body 10.

The inclined wall 12 then divides the interior 15 of the body 10 into chambers of different capacity. The chamber 14 is the larger and is particularly adapted for containing salt, while the chamber 15 is the smaller and is particularly adapted for containing pepper, as usually not as much pepper as salt is used.

A disc shaped cap or cover 16 is provided for closing the upper closed end of the dispenser 10. The cover 16 is formed with a top wall as 17, having depending side flanges 18 fixed to or formed thereon. The inner surface of the side flanges 18 engage the outer surface of the walls 11 of the body 10. The cap 16 is removably secured to the body 10 in such a manner that it may be removed or fastened by partially rotating the cap.

The lower edge of the flange 18 is provided with a downwardly inclined slot 19 on opposite sides thereof, and a downwardly opening slot 20 communicates with the lower end of the inclined slot 19. A pin 21 is fixed to or formed on the outer walls 11 of the body 10 on opposite sides thereof. The cap 16 is secured on the body 10 by positioning the cap so that the pin 21 may engage through the vertical slot 20 as the cap 16 is pressed downward, and as the cap is rotated the pin 21 will engage in the slot 19 frictionally holding the cap on the body.

In order to provide for the installation of the cap 16 on the body 10 so that the cap can be put on in one position only, one of the pins, as 21a, is positioned slightly below the opposite pin 21. The correlated slots on the flange 18 are also positioned slightly lower so that the pin 21a is engageable only in the slots that are correlated with it. In this manner the cap 16 may not be secured to the body 10 in a reversed position.

The top wall 17 of the cap 16 is provided with a segmental cluster of perforations or openings 22 which open downwardly into the chamber 15.

Another segmental cluster of openings, as 24, are provided in the wall 17, which open into the chamber 14.

In order to provide for dispensing the material from the chambers 14 and 15 selectively, a selector plate 27 is rotatably carried by the cap 16. The plate 27 is formed with an upper flat wall 28 which overlies the upper wall 17 of the cover 16. Downwardly extending peripheral flanges 29 are formed on the plate 27 for rotatably engaging about the flanges 18 of the cap 16. The flange 18 is formed with a peripheral groove 30 thereabout, which opens outwardly. The flange 29 of the plate 27 is formed with a correlated annular groove 31 on the inner side thereof, which is adapted to register with the groove 30 when the plate 27 is in its proper position.

For rotatably securing the plate 27 to the cap 16, a spring 32 is engaged in the grooves 30 and 31. The spring 32 is formed of resilient wire, bent into a substantial spiral shape. The inner end of the spring 32 is formed of a diameter less than the diameter of the groove 30 of the cover 16 so that the innermost end 34 of the spring 32 is biased inwardly against the inner wall of the groove 30.

The outer end 35 of the spring 32 is bent in a diameter greater than the diameter of the groove 31 so that this end of the spring is biased outwardly in the plate 27. The groove 30 is of sufficient depth to completely enclose the spring 32 when the spring is compressed, so that the spring may be placed in the groove 30 and held there while the plate 27 is pressed into place.

When the plate 27 is moved so that the groove 31 comes into registry with the groove 30, the end 35 of the spring 32 is pressed outwardly into the groove 31, and the plate 27 is rotatably secured to the cover 16.

The plate 27 is formed with a segmental opening 36 through the top wall 28, the size of the opening 36 being substantially the same as the segments 25 and 26 described above. The segments 25 and 26 are separated a distance greater than each of the segments so that when the plate 27 is positioned, as shown in Figure 1, with the opening 36 between the segments 25 and 26, all of the perforations or openings through the cap are closed. The plate 27 may then be rotated in either direction for selectively opening or uncovering the perforations 24 or 22. The relative rotation of the plate 27 to the cover 16 is limited by a pin or lug 37 fixed to or formed on an annular rib 38 at the lower end of the flange 18. The flange 29 of the plate 27 is formed with an outwardly extending annular recess 39 in which the lug 37 slidably engages. Upon rotation of the plate 27 the lug 37 will engage with the ends of the slot 39 for limiting the rotation of the plate 27. In this manner the opening 36 will be disposed either in registry with the segments 25 or 26, or between them and will be held against further rotation.

I do not mean to confine myself to the exact details of construction herein disclosed, but claim all variations falling within the purview of the appended claims.

What I claim is:

1. A condiment shaker comprising a cylindrical body, a wall in said body forming a pair of chambers therein, a cover for said body, said cover formed with openings communicating with said chambers, an annular flange on said cover engaging about the upper open end of said body, said flange formed with inclined slots, pins on said body engaging in said slots for securing said cover on said body, a selector plate rotatably carried by said cover, a flange on said plate engaging about the flange on said cover, said flanges formed with confronting annular grooves, a spiral resilient split ring engaging in said grooves for rotatably securing said plate on said cover, one end of said ring being biased into engagement with said cover and the other end of said ring biased into engagement with said plate, said plate formed with an opening for selectively registering with the openings in said cover, and correlated means carried by said cover and said plate for limiting the rotation of said plate with respect to said cover.

2. A condiment shaker comprising a cylindrical body, a wall in said body forming a pair of chambers therein, a cover on the top end of said body, said cover formed with openings communicating with said chambers, a selector plate rotatably carried by said cover, a depending flange on the periphery of said plate engaging about said cover, confronting annular grooves formed in said depending flange and in said cover, a spiral resilient split ring engaging in said grooves for rotatably securing said plate on said cover, one end of said ring being biased into engagement with said cover and the other end of said ring biased into engagement with said plate, said plate being formed with an opening for selectively registering with the openings in said cover, and correlated means carried by said cover and said plate for limiting the rotation of said plate with respect to said cover.
